SWITCHING DEVICE FOR CONTROLLING AIRCRAFT INSTRUMENTS

Cecil C. Pine, Floral Park, Herbert C. Bostwick,
Hempstead, Caesar F. Fragola, East Hempstead,
and Francis G. Nesbitt, Garden City, N. Y., as
signors to The Sperry Corporation, Great Neck,
N. Y., a corporation of Delaware

Application May 3, 1949, Serial No. 2,411

Term of patent 14 years

(Cl. D52—1)

To all whom it may concern:

Be it known that we, Cecil C. Pine, Herbert C. Bostwick, Caesar F. Fragola, and Francis G. Nesbitt, citizens of the United States of America, residing at Floral Park, Hempstead, East Hempstead and Garden City, respectively, in the county of Nassau, respectively, and State of New York, have invented a new, original, and ornamental Design for a Switching Device for Controlling Aircraft Instruments, of which the following is a specification, reference being had to the accompanying drawing, forming part thereof.

Fig. 1 is a front elevational view of a switching device for controlling aircraft instruments, showing our new design;

Fig. 2 is a side elevational view with a fragment of the housing shown in broken lines; and

Fig. 3 is a bottom plan view with the housing shown in broken lines.

The dominant features of our design reside in the portion shown in solid lines.

We claim:

The ornamental design for a switching device for controlling aircraft instruments, as shown and described.

CECIL C. PINE.
HERBERT C. BOSTWICK.
CAESAR F. FRAGOLA.
FRANCIS G. NESBITT.
